US0D1014924S

(12) United States Design Patent (10) Patent No.: US D1,014,924 S
(45) Date of Patent:  Feb. 20, 2024

(54) SHOE

(71) Applicant: NIKE, Inc., Beaverton, OR (US)

(72) Inventor: Nathan G. Schultze, Portland, OR (US)

(73) Assignee: NIKE, Inc., Beaverton, OR (US)

() Term: 15 Years

(21) Appl. No.: 29/846,424

(22) Filed: Jul. 15, 2022

(51) LOC (14) Cl. 02-04

(52) U.S. Cl.

USPC D2/947; D2/926

(58) Field of Classification Search

USPC D2/902, 907-909, 911, 919, 923,

D2/946-947, 976-977

CPC A43B 1/04; A43B 23/24; A43B 3/0031;

A43B 3/101; A43B 3/102; A43B 3/35;

A43B 5/06; A43B 5/10

(57) CLAIM

The ornamental design for a shoe, as shown and described.

DESCRIPTION

FIG. 1 is a front perspective view of a shoe showing my new design;

FIG. 2 is a side view thereof;

FIG. 3 is a top view thereof;

FIG. 4 is an opposite side view thereof; and,

FIG. 5 is an opposite side front perspective view thereof. The broken lines and unshaded areas depicting the remainder of the shoe form no part of the claimed design.

1 Claim, 5 Drawing Sheets
